UNITED STATES PATENT OFFICE.

JOHN C. FREDRICKSEN, OF MILLER, INDIANA, ASSIGNOR TO JOHN C. FREDRICKSEN
MANUFACTURING CO., OF MILLER, INDIANA, A CORPORATION OF INDIANA.

EXPLOSIVE-ENGINE.

1,318,371.

Specification of Letters Patent. Patented Oct. 14, 1919.

Application filed May 5, 1917. Serial No. 166,608.

To all whom it may concern:

Be it known that I, JOHN C. FREDRICKSEN, a citizen of the United States, and a resident of the city of Miller, county of 5 Lake, and State of Indiana, have invented certain new and useful Improvements in Explosive-Engines, of which the following is a specification.

My invention relates to improvements in 10 explosive engines and has for its object the provision of an improved engine of this character capable of operating with great efficiency.

The invention consists in the combinations 15 and arrangements of parts hereinafter described and claimed.

The invention will be best understood by reference to the accompanying drawings forming a part of this specification, and in 20 which,

Figure 1 is a sectional view of an explosive engine operating on the two cycle principle embodying my invention,

Fig. 2, a top plan view of the same, and 25 Fig. 3, a detail view of the cylinder head removed.

The form of construction illustrated in Figs. 1, 2 and 3 comprises a suitable crank case 5 having an engine cylinder 6 mounted thereon, the inner end 7 of said engine cylinder being reduced in size to substantially half the size of the main cylinder. A cylinder head 8 in the form of a piston is arranged to slide in the outer end of cylinder 6 being mounted upon a guide rod 9 operating through a guide 10, as indicated, a compression spring 11 being interposed between cylinder head 8 and guide 10 and the parts being arranged to normally hold the cylinder head 8 in the neighborhood of the operative center of cylinder 6. A hollow piston 12 is arranged to operate in cylinder 6 and is provided with a reduced extension 13 open at its inner end 14 and operating as 45 a piston in the cylinder extension 7. The piston 12-13 is operatively connected by one or more piston rods 15 with the usual crank shaft 16 mounted in the crank case 5. An inlet opening 17 is provided at the inner 50 end of the cylinder extension 7 for connection with an ordinary carburetor for supplying the explosive mixture to the engine and air openings 18 are provided at the inner end of cylinder 6 to provide free access of 55 air thereto. The piston 12-13 is provided

with a port 19 coöperating with a by-pass 20 in the wall of cylinder 6 in the usual manner to transfer explosive mixture in the cylinder 6 in the usual manner. A spark plug 21 is located in the wall of cylinder 6 60 to register with the space between the cylinder head 8 and the piston 12 when both are at the outer ends of their movements.

In operation, the explosive mixture is drawn into the cylinder extension 7 and 65 compressed therein in the usual manner and passes into the cylinder 6 through the by-pass 20 when the piston 12-13 reaches the inner end of its stroke. On the compression stroke of the piston 12 the charge is compressed against the cylinder head 8 which in turn is moved upwardly until it rests against the outer end of the cylinder, in which position the spark plug 21 will be in communication with the explosive charge. The 70 charge is exploded by the spark plug 21 in the usual manner and causes operation of the piston in the usual manner. The charge is exhausted through the usual exhaust port 20' at the inner end of the stroke of the 75 piston 12 the engine operating on the well known two cycle plan. By this arrangement complete scavenging of the cylinder 6 and complete combustion of the charge therein is assured. The complete scavenging is effected 80 due to the fact that the cylinder head 8 moves up to a position midway of the cylinder at the time of exhaust and at the same time a previously prepared charge of sufficient volume to completely fill the fuel 85 space of the cylinder is admitted under circumstances compelling the complete expulsion of the burnt gases. The complete combustion of the charge is effected by virtue of the fact that the same is ignited under heavy 90 compression and a prolonged expansion of the burning gases obtained by virtue of the fact that the cylinder head 8 does not move up to exhausting position until exhaust takes place. The cylinder 6 is air cooled at 95 both ends and the explosive charge is small in relation to the other parts, thus dispensing with the necessity for a water jacket in small sized engines. By this arrangement also, the explosive charge expands almost 100 to atmospheric pressure thus tending to provide a noiselessly operating engine and increasing the efficiency.

While I have illustrated and described the preferred forms of construction for car- 110

rying my invention into effect, these are capable of variation and modification without departing from the spirit of the invention. I, therefore, do not wish to be limited 5 to the precise details of construction set forth, but desire to avail myself of such variations and modifications as come within the scope of the appended claims.

Having described my invention what I 10 claim as new and desire to secure by Letters Patent is:

1. An explosive engine comprising a cylinder having a reduced coaxial extension leading therefrom and closed at its end opposite said cylinder; and a piston operating 15 in said cylinder and having a reduced extension operating in said cylinder extension, said piston being hollow, open at the end operating in said extension, and provided

20 with a port in the portion operating in said cylinder, there being a by-pass in the walls of said cylinder arranged to transfer the charge from said piston through said port into said cylinder, there being a charge intake at the inner end of the reduced portion 25 of said cylinder, substantially as described.

2. An explosive engine comprising a cylinder having a reduced coaxial extension leading therefrom and closed at its end opposite said cylinder; and a piston operating 30 in said cylinder and having a reduced extension operating in said cylinder extension, said piston being hollow, open at the end operating in said extension, and provided 35 with a port in the part operating in said cylinder, there being a by-pass in the walls of

said cylinder arranged to transfer the charge from said piston through said port into said cylinder, there being a charge intake at the inner end of the reduced portion 40 of said cylinder, and an air opening leading into the end of said cylinder adjacent said cylinder extension, substantially as described.

3. An explosive engine comprising a cylinder 45 having a reduced coaxial extension in open communication therewith but closed at the end opposite said cylinder; a piston operating in said cylinder and having a reduced coaxial extension operating in said cylinder extension, said piston being hollow, open at its inner end and provided with a port in its outer portion, there being a by-pass in the walls of said cylinder arranged to transfer the charge from said piston 50 through said port into said cylinder, there being a charge intake at the inner end of the reduced portion of said cylinder, and an air opening at the inner end of said cylinder; a cylinder head in the form of a piston 55 sliding in said cylinder; and yieldable means for normally holding said cylinder head in the neighborhood of the normal operative center of said cylinder, substantially as described.

In testimony whereof I have signed my name to this specification in the presence of two subscribing witnesses.

JOHN C. FREDRICKSEN.
